(57) **CLAIM**

The ornamental design for a caliper for disc brakes as shown and described.

DESCRIPTION

FIG. 1 is a top, front, left side perspective view of a first embodiment of the caliper for disc brakes of my new design; FIG. 2 is a left side elevation view thereof;

FIG. 3 is a front elevation view thereof;

FIG. 4 is a rear elevation view thereof;

FIG. 5 is a bottom plan view thereof;

FIG. 6 is a top plan view thereof;

FIG. 7 is a right side elevation view thereof;

FIG. 8 is a top, front, left side perspective view of a second embodiment of the caliper for disc brakes of my new design; FIG. 9 is a left side elevation view thereof;

FIG. 10 is a front elevation view thereof;

FIG. 11 is a right side elevation view thereof;

FIG. 12 is a top plan view thereof;

FIG. 13 is a top, left side perspective view of a third embodiment of the caliper for disc brakes of my new design; FIG. 14 is a left side elevation view thereof;

FIG. 15 is a right side elevation view thereof;

FIG. 16 is a bottom plan view thereof;

FIG. 17 is a front elevation view thereof;

FIG. 18 is a rear elevation view thereof;

FIG. 19 is a top plan view thereof; and,

FIG. 20 is a bottom, front left side perspective view thereof. The broken lines illustrate portions of the caliper for disc brakes which form no part of the claimed design.
